US0D1007261S

(12) **United States Design Patent** (10) **Patent No.:** **US D1,007,261 S**
(45) **Date of Patent:** **** Dec. 12, 2023**

(54) **TREE CLIMBING TOOL**

(71) Applicant: **Ming Xue**, Shenzhen Guangdong (CN)

(72) Inventor: **Ming Xue**, Shenzhen Guangdong (CN)

(**) Term: **15 Years**

(21) Appl. No.: **29/898,282**

(22) Filed: **Jul. 25, 2023**

(51) LOC (14) Cl. **25-04**

(52) U.S. Cl.

USPC **D25/64**; D8/1

(58) **Field of Classification Search**

USPC D25/64, 69; D8/1
CPC E06C 1/381; E06C 1/34

See application file for complete search history.

(57) **CLAIM**

The ornamental design for a tree climbing tool, as shown and described.

DESCRIPTION

FIG. 1 is a front, right and top perspective view of a tree climbing tool, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the tree climbing tool that form no part of the claimed design.

1 Claim, 8 Drawing Sheets
